UNITED STATES PATENT OFFICE

159,734

MEAT SLICER

Edward C. Karp, Belvidere, Ill., assignor to Sanitary Scale Company, Belvidere, Ill., a corporation of Illinois

Application February 24, 1950, Serial No. 8,109

Term of patent 14 years

(Cl. D55—1)

To all whom it may concern:

Be it known that I, Edward C. Karp, a citizen of the United States, residing at Belvidere, in the county of Boone and State of Illinois, have invented a new, original, and ornamental Design for a Meat Slicer, of which the following is a specification, reference being made to the accompanying drawings, forming a part thereof.

In the drawings:

I claim:

The ornamental design for a meat slicer, substantially as shown.

EDWARD C. KARP.
